Primary Examiner — Jennifer Rivard*Assistant Examiner* — Catherine S Posthauer*(74) Attorney, Agent, or Firm* — Wenderoth, Lind & Ponack, L.L.P.(57) CLAIM

The ornamental design for a closed stopper, as shown and described.

DESCRIPTION

FIG. 1 is a perspective view of the closed stopper;

FIG. 2 is a front view of the closed stopper;

FIG. 3 is a right side view of the closed stopper;

FIG. 4 is a left side view of the closed stopper;

FIG. 5 is a back view of the closed stopper;

FIG. 6 is a bottom view of the closed stopper; and,

FIG. 7 is a top view of the closed stopper.

The broken lines are shown for the purpose of illustrating parts of the article that form no part of the claim.

1 Claim, 7 Drawing Sheets(56)
